United States Patent Office

Des. 210,486
Patented Mar. 12, 1968

210,486

ELECTRIC IRON OR SIMILAR ARTICLE

John C. Shalvoy, Fairfield, Conn., assignor to General
Electric Company, a corporation of New York

Filed Sept. 12, 1967, Ser. No. 8,572

Term of patent 14 years

(Cl. D49—6)

Fig. 1.

Fig. 2.

Fig. 3.

Fig. 4.

Fig. 5.

FIG. 1 is a perspective view of an electric iron or similar article embodying my new design;

FIG. 2 is a side elevational view thereof;

FIG. 3 is a top plan view thereof;

FIG. 4 is a front elevational view thereof; and

FIG. 5 is a rear elevational view thereof.

The dominant features of my design reside in the portions shown in full lines.

I claim:

The ornamental design for an electric iron or similar article, substantially as shown and described.
